United States Patent Office

Des. 233,882
Patented Dec. 10, 1974

233,882

PACKAGING CUP

David K. Domnitz, Waukegan, Ill., assignor to Kraftco Corporation, Glenview, Ill.

Filed Jan. 23, 1973, Ser. No. 326,049

Term of patent 14 years

Int. Cl. D9—03

U.S. Cl. D9—219

FIG. 1

FIG. 2

FIG. 3

FIG. 4

FIG. 5

FIG. 1 is a top plan view of a packaging cup showing my new design;

FIG. 2 is a side view thereof in elevation, each side view thereof being identical as said packaging cup is revolved through 120 degrees;

FIG. 3 is a bottom plan view thereof;

FIG. 4 is a side view thereof in elevation opposite to said side view of FIG. 2; and

FIG. 5 is a cross-sectional view taken through line 5—5 of FIG. 3.

I claim:

The ornamental design for a packaging cup, substantially as shown and described.
